UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

DUSTLESS ROCK DRILL.

Application filed November 12, 1924. Serial No. 749,374.

To all whom it may concern:

Be it known that I, CHARLES C. HANSEN, a citizen of the United States, and a resident of Easton, county of Northampton, 5 State of Pennsylvania, have invented a certain Dustless Rock Drill, of which the following is a specification accompanied by drawings.

This invention relates to fluid actuated 10 rock drills of the hammer type, but more particularly to rock drills in which motive fluid is prevented from passing through the drill steel into the drill hole.

Rock drills employed in mining and similar operations are usually provided with means for cleansing the drill hole, which may consist of a tube or tubes extending centrally through the drill and communicating at their forward ends with the hollow bore of the drill steel, thus forming a direct path for the cleansing fluids from their respective sources of supply to the drill hole for removing cuttings. The cuttings removed from the hole are for the most part wet 20 but due to the presence of motive fluid leaking from the cylinder under pressure into the drill steel along with the water, some of the finer rock particles are blown out of the drill hole as dust or suspended in a mist. In 25 some instances, owing to the particular nature of the rock being drilled, the inhalation of dust is injurious to the health of the operator.

It has been found that a rock drill may be 30 constructed so that motive fluid leaking past the percussive elements toward the front end of the drill may be exhausted through suitable channels directly from the interior of the drill to atmosphere, thus preventing 35 leakage of the motive fluid into the drill hole and consequently preventing the formation of mist. The principal object of this invention is to prevent the passage of leakage air into a drill hole by exhausting it 40 directly from the interior of the drill to atmosphere.

Other objects will hereinafter be pointed 45 out, and the invention is illustrated in one of its preferred forms in the accompanying drawings, in which—

Figure 1 is a longitudinal elevation partly in section of a hand held dustless rock drill, and

Figure 2 is a transverse view taken through Figure 1 on the line 2—2 looking 55 in the direction of the arrows.

Referring to the drawings in which the invention is shown embodied in a rock drill of the hand held type, a cylinder A, a front head B and a back head C having a suitable handle, are held in operative relation by the usual side bolts (not shown). Disposed within the cylinder is a reciprocatory hammer piston D, having a head, and a fluted reduced cylindrical forward extension to deliver blows upon a hollow drill steel E, extending into the forward end of the front head B and held in alignment by means of a chuck bushing F, which in this instance is press fitted into a hollow bore in the forward end of a chuck G, and rotatable therewith within the front head B. Motive fluid is supplied to the drill through a conduit H and is distributed by a suitable valve (not shown) in a valve chest J.

In order to supply cleansing liquid, such as water, to the drill hole, a tube K having a reduced forward end and supported at its rearward end within the back head C, is arranged centrally through the percussive element and extends at its forward end into the drill steel E. Rotation of the drill steel is in this instance effected by a rifle bar L, having a fluted reduced forward extension and a head supporting a plurality of pawls 85 which cooperate with a suitable rotation ratchet O, while the fluted extension of the rifle bar L cooperates with the rifle nut P, arranged in the head of the piston D, said nut being preferably held therein by means 90 of screw threads. The chuck G is provided with internal flutes Q cooperating with the flutes in the forward extension of the piston D. By this arrangement of parts, a flexible train of cooperating elements is provided for 95 rotating the steel E, thereby keeping the steel free within the drill hole.

Means are provided for preventing the motive fluid leaking out of the forward end of the cylinder A from passing through the 100 drill steel E to the drill hole. To this end the front cylinder washer R is formed with cylindrical rearward and forward extensions which are adapted to project into suitable bores within the cylinder A and the 105 front head B respectively. Within the

washer R there is provided a hollow bore to receive the forward extension of the piston D. An annular recess S is formed in the bore of the washer R and a plurality of grooves T are formed radially across the face of the washer communicating with the recess S and with the atmosphere through an internal annular groove U in the front head adjacent the grooves T, and a plurality of holes V through the front head from the annular groove U.

In this way any motive fluid leaking past the forward extension of the piston D will be exhausted to atmosphere directly from the interior of the drill instead of passing through the drill steel as heretofore.

Many drills designed to utilize air for blowing through the steel may be changed to eliminate the admission of air into the steel by grinding the grooves S, T and U and the holes V in the corresponding parts. On occasions a puff of air to the drill steel may be desirable, and this may be produced by covering the holes V in any suitable manner as for instance, by the hand, whereupon the air under pressure will pass through the hollow drill steel E in the same manner as in drills which are not provided with this dustless feature.

I claim:

1. A fluid actuated rock drill comprising a cylinder, a hammer piston having a reduced forward cylindrical extension to reciprocate within the cylinder, a front head having an internal annular groove near its rearward end and a plurality of holes extending from the groove through the wall of the front head whereby said groove may communicate with the atmosphere, a front

cylinder washer having a hollow bore to receive the forward extension of the hammer piston arranged within the front head, said washer having rearward and forward extensions extending within the cylinder and front head respectively, and an internal annular recess in its forward extension, and a plurality of radial grooves in the forward face of the forward extension communicating with the said internal recess and with the annular groove in the front head to permit the exhaust of leakage motive fluid to atmosphere through the side of the front head.

2. A fluid actuated rock drill comprising a cylinder, a hammer piston having a reduced forward cylindrical extension to reciprocate within the cylinder, a front head having an internal annular groove near its rearward end and a plurality of holes extending from the groove through the wall of the front head whereby said groove may communicate with the atmosphere, a hollow front cylinder washer, said washer having a short rearward extension to project into the cylinder and a long forward extension to project into the front head, an internal annular recess at the end of the forward extension, a plurality of grooves formed radially in the end face of the forward extension communicating with the said internal recess and with the annular groove in the front head to permit the exhaust of leakage motive fluid from the interior of the chuck and from the front head to atmosphere.

In testimony whereof I have signed this specification.

CHARLES C. HANSEN.
